UNITED STATES PATENT OFFICE

2,604,768

KNITTING MACHINE

John E. Schuster, Washington, D. C.

Application August 8, 1947, Serial No. 767,503

4 Claims. (Cl. 66—86)

1

The present invention relates to new and improved knitting machines of the so-called Raschel-type.

A primary object of the invention is the embodiment of a machine of the aforesaid type which is characterized by relative simplicity of construction, compactness of arrangement, accessibility of parts for adjustment, replacement or repair, adaptability for simultaneous manufacture of a plurality of knit products, independence of parts whereby the specific character of the several products being made may be individually and independently varied, freedom from objectionable protuberances, capacity for operation at higher than normal speeds without objectionable vibration, highly enhanced output, etc.

Other objects will be apparent from the following detailed description of constructional embodiments of machines according to the invention.

To this end, the invention comprises the relationships of parts shown on the accompanying sheets of drawing and described in detail, by way of example, in the following specification:

On the said sheets of drawing,

Fig. 1 is a perspective view of one embodiment of machine according to the present invention, as seen from one end thereof;

Fig. 2 is a fragmentary elevational view of the said end of the said embodiment, on a relatively enlarged scale;

Fig. 3 is an elevational view of a portion of the other end of the aforesaid embodiment of the machine according to the invention;

Fig. 4 is a front elevation of a portion of the machine showing more particularly details of the knitting mechanism;

Fig. 4A is an elevational view of a terminal bracket and guide pins;

Fig. 5 is a sectional view (upper portion) taken along line 5—5 of Fig. 4;

Fig. 5A is a sectional view (lower portion) taken along line 5—5 of Fig. 4;

Fig. 6 is a fragmentary elevation, viewed from the front of the machine, and showing the main driving arrangement;

Figs. 7 and 8 are fragmentary views showing the mode of driving the monitor head, actuating the cloth take-up mechanism, and driving the knitting mechanism and the work take-up mechanism, Fig. 8 being taken along line 8—8 of Fig. 7;

Fig. 9 is a perspective view of an end of a second embodiment of machine according to the invention;

2

Figs. 10 and 11 are, respectively, fragmentary elevational and sectional views of one embodiment of reed suspending means, Fig. 11 being taken along line 11—11 of Fig. 10;

Fig. 12 is a perspective view of monitor head; and

Fig. 13 is an elevational view of a modified form of work take-up mechanism.

The warp knitting machine according to the present invention comprises a number of major parts, essentially as follows:

- (a) The machine frame;
- (b) The driving mechanism;
- (c) The dual knitting mechanism;
- (d) The work take-up mechanism; and
- (e) The cloth take-up mechanism.

(a) *The machine frame*

This consists essentially of a pair of side walls 10, 11 interconnected by suitably arranged transverse bars or beams 12. The lower part of the frame supports the driving mechanism. The knitting mechanism is arranged substantially centrally of the frame. The upper part of the frame assumes the form of a beam tree 13 for the requisite beams and rolls of yarn. On the exterior of one of the frame sides is arranged the work take-up mechanism and the monitor head, while on the exterior of the other frame side is the cloth take-up mechanism and the needle bar oscillating mechanism.

As will hereinafter appear, the machine frame is of such configuration and the several mechanisms are so arranged thereon that a relatively compact machine results—much more compact than comparable prior art machines. Additional features of the arrangement are that there are no substantial protuberances—other than the conventional monitor head—beyond the limits of the machine frame. Even the driving motor is disposed within the confines of the latter. Moreover, all the operating parts are readily accessible for adjustment, repair and/or removal. The beam tree is formed so that the beams and rolls thereon do not interfere with the work of the operator but are nevertheless readily accessible.

(b) *The driving mechanism*

The source of power is an electric motor 14 (Fig. 6) of suitable capacity for driving the machine at variable speeds up to as high as or greater than 400 rows per minute. The motor is mounted centrally and inwardly of the front of the machine. A gear casing 15 containing suitably proportioned reducing gearing or the

like is arranged above the motor casing, the gearing being driven in conventional manner from the motor. This gearing is connected via a toothed coupling 16 or the like on each side to the corresponding half 17 of a split main drive shaft. The drive shaft halves 17 are respectively journaled at their other ends in one of the side walls of the frame.

Just inside each side wall, an adjustable high speed needle bar cam 18 is mounted on each drive shaft element 17. Each such cam cooperates with an eccentric 19 whereby an integrally connected lever arm 20 oscillatably reciprocates in the vertical direction. The top of each lever arm is pivotally connected to a vertically reciprocal slide 21 which moves in a slide box 22 (Fig. 5A) affixed to the inner surface of the corresponding side frame wall.

As will hereinafter appear, this arrangement drives the needle bar of the machine.

The main driving shaft element 17, on one side of the machine, extends through the side wall 11, on the exterior of which it is provided with an eccentrically disposed cam 23 (Fig. 3) which, as hereinafter explained, constitutes in effect the driving means for the work take-up mechanism.

This same main driving shaft element is provided, just inside the frame side wall 11 in which it is journaled, and therebetween and the first described cam member 19, with a sprocket gear 24 (Figs. 6 and 7) from which, by way of a sprocket chain running over the gears 25, 26 mounted on the frame 11, a pinion 27 mounted on the outside of the frame adjacent the monitor head is actuated. This pinion 27 engages a bevel gear 28 mounted on the end of the monitor head shaft 29. This in effect constitutes the driving means for the monitor head.

The other end of the other main drive shaft element 17, projects beyond the other frame wall 10, in which it is journaled, and has a pear-shaped box cam 30 (Figs. 1 and 2) mounted thereon. This provides the means for actuating the dual swing bar shafts, hereinafter referred to.

It is thus apparent that an efficient driving means is provided whereby, from a single centrally-positioned power source 14, a plurality of elements and mechanisms are actuated through the medium of a pair of main driving shaft halves 17. This arrangement avoids the necessity of dismantling the entire machine when repair or replacement is necessary on one side—only the involved side being taken down.

In order to allow minor adjustments to be made, means may be provided whereby the machine may be manually actuated. To this end, a handwheel element 31 may be provided (Fig. 6), rotation of which actuates the gearing in box 15. During actuation from the motor 14, the power transmitting element 32 (belt, sprocket chain, or the like) is loosened, handwheel 31 being mounted on an eccentric bearing for this purpose.

(c) *The dual knitting mechanism*

The upper end of each slide 21 (Figs. 5 and 5A) is bolted at 33 to a channel-shaped needle bar 34. Secured in any suitable and desirable manner, as by means of members 35, to each upwardly-extending vertical leg of the said needle bar is a row of needles 36, whereby two parallel spaced rows of needles results.

A stationary face plate 37 is adjustably secured, by means of bolts or the like, to each side of each of the aforesaid slide boxes 22, the inner surface of each face plate being arranged in juxtaposition

to the adjacent vertical leg of the needle bar 34. The latter thus reciprocates between the opposite surfaces of the two face plates. To facilitate the sliding movement between the juxtaposed surfaces of members 34 and 37, the inner surface of each of the latter may be provided with lubricating inserts (graphitic studs or the like).

As will hereinafter appear, the material being knitted moves from the hooks of the needles over the front or outer surface of each face plate to its respective work take-up roller (hereinafter described).

An important feature of the invention, in its preferred embodiment, is its dual aspect. This is realized by the provision of two, instead of one, guide bar swing shafts 38, 39, the guides 40 on the guide bars 41 depending from each swing shaft cooperating with the corresponding row of needles. This dual arrangement, as will become clear as the description progresses, makes possible the relatively high speed of the new knitting machine, since each swing shaft and associated parts in effect constitutes an inertia cushion or counterbalance of the other swing shaft and its associated parts whereby the chattering or undue vibration encountered at high speeds in single swing shaft machines is effectively eliminated.

If desired, and as shown in Figs. 5 and 5A, it is possible, with the machine of the invention, to provide as many as 3 rows of needles 36 and as many as 3-5 rows of guides 40. The third row of needles involves the provision of an additional fixed face plate 37' and slide box 22' and also of an additional reciprocable needle bar 34'. Reciprocation of the latter may be realized by means of connecting links 42, 43. It will be understood that parts 42, 43, 22', 34' and 37' may be omitted, in which case connection between parts 20 and 21 (Fig. 5A) will be by means of a simple articulating linkage.

As hereinbefore indicated, the swing shafts 38, 39 are actuated for oscillation from the main drive shaft 17 via the pear-shaped box cam 30 thereon. A vertically reciprocable driving bar 44 is provided (Figs. 1 and 2) which has, at its lower end, a cam roller 45 which rolls in the recess or groove 46 of the box cam, whereby a positive drive of the said bar in both directions is realized. The said vertically reciprocable driving bar is arranged for movement in a slide box 47 fixed to the outside of the corresponding side wall 10 of the frame.

The swing shafts 38, 39 themselves are positioned above the needle rows with their ends journaled in the frame walls, one end of each swing shaft projecting outwardly beyond that wall 10 on which the aforementioned driving bar 44 is arranged. Integrally associated with the projecting end of the first guide bar swing shaft 39 is a slotted arm 48, the slotted extension of which is associated with the upper end of an adjuster link 49, the lower end of which is pivotally connected at pivot 50 to the aforementioned driving bar 44. Reciprocation of the latter, upon rotation of the box cam, effects oscillation of the slotted arm 48 and therewith of the first swing shaft 39. The extent of the stroke may be varied by adjusting the adjuster link 49 relative to the slot in arm 48 whereby displacement of the pin in the slot is effected. Further adjustment is also possible with the aid of the angular adjusting piece 51 which is fixed to the end of the swing shaft by means of pins 52. Adjusting screws 53 threaded through lugs extending from the periphery of the upper end of the slotted arm 48 are adjustable with respect to the angular adjusting piece 51. The radial screws

(not shown) which hold the arm 48 in place on the shaft end are first loosened, then the position of the arm on the shaft adjusted by turning the adjusting screws 53—and the radial screws tightened when the desired relative disposition of arm and shaft is realized.

Secured to the projecting end of the second guide bar swing shaft 38 is a second arm 54 comprising essentially an annulus securable to the shaft end and an obliquely upwardly extending lug, the latter being provided with a plurality of perforations or bores 55 extending therethrough. A connect-link 56 extends from the first arm 48 to this second arm 54. The lower end of the said link 56 extends through the slotted portion of the first arm 48, while its upper end is secured in one of the aforesaid perforations or bores 55, the number and disposition of the latter affording a means of adjustment. It will be manifest from the foregoing that means are thus provided for the simultaneous oscillation—with possibilities of relative adjustment of strokes—of the two guide bar swing shafts 38 and 39. It is noteworthy in this regard that the adjustments of the two swing bars are wholly independent of each other, which is desirable since each bar may be involved in an entirely different piece of work from the other. It is also possible wholly to dissociate the second swing bar from the first, if desired, whereby in effect a single swing shaft machine is realized.

Depending from each swing shaft at spaced intervals therealong (see Fig. 4) is a bracket 59 (see also Fig. 5), the lower portion of which is subdivided into a plurality of segments. From each segment, a steadier 60 may depend, the connection between the segment and steadier being such as to allow of their relative adjustment. The lower end of each steadier is provided with a bore. A steadier pin 61 extends through each said bore, the ends of the pin being secured in lugs 62 integrated with and upstanding from the guide bar 41 therebeneath. A coil spring 63 is arranged on each steadier pin 61 between the steadier 60 and one of the said lugs 62.

It is clear from the foregoing that upon the swinging of either swing shaft, the guide bars 41 associated therewith in the above-described manner will be entrained, i. e. will swing or oscillate therewith.

However, it is also necessary that the guide bars 41 be reciprocable as well as oscillatable. To this end, a special terminal bracket 64 (Figs. 4 and 4A) is provided at each end of each swing shaft 38 and 39. Each terminal bracket 64 is provided with a number of horizontally extending pins 65, corresponding in number to the number of guide bars 41. At each end of each guide bar, there is a special upstanding terminal lug 66 which is provided with a bore which fits over the corresponding pin 65 of the terminal bracket 64. Slide bearings for the guide bars 41 are thus provided. At the end nearest the monitor head, each guide bar 41 is provided with means for association with a pull chain or bar 67 (Figs. 7 and 12).

The monitor head 68 (which may be encased as at 69 in Fig. 7 or may be exposed as in Fig. 12) is of generally conventional construction but is much larger than usual in order that it may accommodate 8-10 cam chains. The monitor head is mounted on a bracket 70 (see Fig. 12) which provides the journal means for the monitor head drum shaft, on which the chain cams

are wound in spaced relation. Above the monitor head drum is an upper pivot shaft 71 on which are pivoted a number of L-shaped cam roller members 72, corresponding in number to the number of chain cams and to the maximum number of guide bars.

The vertical leg of each L-shaped member is adjustably connected to one end of a chain or bar 67, the other end of which is securable to the corresponding guide bar 41. The horizontal leg of each L-shaped member is provided with a cam roller 73 which coacts with the chain cam, whereby, at the desired moment, a pull is exerted on the corresponding guide bar 41 through its chain or rod 67 and against the action of the aforementioned coil spring 63 which tends to pull the guide bar 41 in the other direction. The chain cams on the monitor head correlate the pulls to the oscillatory movements of the swing shafts 38 and 39 and to the vertical reciprocatory movements of the needles in accordance with the desired knitting pattern. Each pull chain or rod 67 can be disconnected from its guide bar 41 when the latter is not to be used, and the entire L-shaped cam member can be swung over out of the way. The cams and the adjustable connections enable variable and independent adjustments to be made.

(d) *The work take-up mechanism*

Two sets of emery surfaced work take-up rollers 74 (Fig. 2) are provided, one pair for each needle row. For positive interconnection, the rollers of each pair are preferably provided adjacent the ends thereof with intermeshing gears. As the take-up rollers are rotated in the manner hereinafter described, the material being knitted goes in therebetween, passing behind the top roller and over and in front of the bottom roller, then back to a guide rod and down to its corresponding cloth take-up roller.

A dual ratchet take-up mechanism is provided on the one side wall 11 of the frame under the monitor head assembly previously described. The shaft of the lower one of each pair of take-up rollers 74 extends through a bearing and beyond the frame wall has a large ratchet wheel 75 mounted thereon. A mounting plate 76 is attached to the outside of the frame and is provided with a pair of spaced guideways 77 in which a roller lift slide 78 can reciprocate. A roller 79 is mounted on said slide. This roller 79 coacts with the cam 23 mounted on the projecting end of the main drive shaft element, hereinbefore described, and is periodically engaged by such cam. This engagement results in a periodic lifting of the lift slide 78. The upper end of the lift slide terminates in a projecting button or teat 80.

Pivoted to the mounting plate 76 at 81 are a pair of tongue-and-socket intermeshed slotted levers 82, the intermeshed inner ends of which are periodically engaged and lifted by the aforesaid teat 80. This lifting of the inner ends of the said levers 82 results in a concomitant downward movement of the outer slotted end of each said lever 82. Pivoted at 83 to each said outer end is an upwardly extending pawl-carrying arm 84, the slot of the lever enabling adjustment of the precise position of the lever. As the outer end of each lever 82 is periodically moved downwardly, as aforescribed, the pawl 85 mounted on each pawl-arm 84 and which is in engagement with one of said ratchet wheels 75 moves the latter, whereby the corresponding pair of take-up rollers 74 is correspondingly entrained. Spring means are provided to keep each pawl

in constant engagement with its ratchet wheel and each wheel is prevented from effecting undesired retrograde movement by a pawl 86 in engagement therewith and mounted on the machine frame. Spring means 87 are also provided for moving the inner ends of the aforesaid levers 82 down again when the lifting teat 80 makes its downward stroke.

A modified form of dual ratchet take-up mechanism is illustrated in Fig. 13. Like the previously described work take-up mechanism, this is arranged on the exterior of wall 11. In so far as the same reference numerals are used on Fig. 13, the identified parts are identical with those of the previously-described work take-up mechanism.

Ratchet wheels 75 are, as before, mounted on the respective take-up roller shafts 74. Parts 76, 77, 78, 79 and 80 are provided as in the previous embodiment, as is also the actuating cam 23. Pivoted to the plate 16 at 81 are the tongue-and-socket intermeshed levers 82', the intermeshed ends of which are periodically lifted by teat 80 and periodically moved down again by spring 87. Pivoted at 100 to each lever 82' is a pawl arm 101. Spring means 102 are provided for keeping the respective pawl arms 101 in engagement with the adjacent ratchet wheels 75.

As the inner ends of levers 82' are periodically lifted, the outer ends—and therewith the pawl arms 101 and pawls thereon, which are in engagement with the ratchet wheels—are moved down, a corresponding rotary displacement of the latter being thus periodically realized. Slot-and-bolt means may be provided for adjusting the length of the arms 101. Screw-bolt means 102 may also be provided for adjusting the position of slide 78.

(e) *The cloth take-up mechanism*

As hereinbefore indicated, as the work passes from the work take-up roller, it goes to its respective cloth take-up roller 88 where it is wound on a spool or the like. The shafts on which the cloth take-up rollers 88 are mounted are provided, one above the other, at the bottom rear of the machine (Fig. 1). The mechanism which is provided, according to the invention, for the take-up of these rollers involves an actuating mercury switch 90 (Fig. 7) on the monitor head side of the machine and a solenoid arrangement on the other side of the machine.

A cam 91 (Fig. 7) is provided on the side of the monitor head drum, which cam periodically engages and lifts the mercury switch 90 pivotally mounted on the machine frame at 92, whereby at each lift the switch 90 is closed. This closing of the switch actuates the aforesaid solenoid arrangement at the other end of the machine. Spring means may be provided for returning the switch to its original disconnected position, or this may be effected by gravity.

At the other end of the machine (see Fig. 2), a pair of guide boxes 93 arranged one above the other are provided in juxtaposition to the cloth rollers 88. A reciprocal slide element 94 is slideable in each box 93. The upper end of each slide element 94 is connected to or itself constitutes the core of a solenoid 95, two of which—connected in series—are provided. These solenoids are actuated upon the closing of the aforesaid mercury switch 90 and lift their respective slide elements 94.

Each slide element 94 carries a pawl 96 which, through the medium of a spring, is kept in con-

stant engagement with the corresponding ratchet wheel 98 mounted on the corresponding take-up roller shaft 88. Spring means 97 are provided which exert a downward pull on each slide element 94 and thereby on its related ratchet wheel 98 so that the cloth being wound on the rollers 88 is constantly kept in the correct state of tension. A retrograde-movement-preventing pawl 99 is provided for each ratchet wheel 98.

Single swing shaft machine

While, for the reasons hereinbefore set forth, the dual machine as described constitutes the preferred form of the invention, the basic principles underlying the invention may also be embodied in a single swing shaft machine, as shown more particularly in Figs. 9 and 12.

In this embodiment, the machine frame is essentially identical with that of the dual machine as described hereinbefore under (a). Moreover, the driving mechanism, as described under (b), is also essentially the same here. The knitting mechanism is the same in so far as the needle bar arrangement is concerned. However, instead of two guide bar swing shafts, only one 38' is provided. Actuation of this swing shaft may be accomplished from the main shaft 17 via cam 102 mounted thereon outside of side wall 10'. This cam effects reciprocation of slide rod 103 which slides in slide box 104 which is lubricated by a graphitic lubricant composition or the like. Reciprocation of rod 103 produces a corresponding reciprocation of bar 105 which is pivotally connected at one end to rod 103 and at the other end to lever 106 which is fixed onto shaft 38'. Movement of bar 105 effects oscillation of lever 106 and, therewith, of shaft 38'.

The work take-up mechanism and cloth take-up mechanism may be essentially of the type hereinbefore described, suitably modified in view of the single swing shaft character of the machine. Thus, for example, the arrangement according to Fig. 13 may be used for the work take-up, omitting the right-hand lever 82' and all parts to the right thereof, as shown on Fig. 13. The cloth take-up may comprise a single solenoid-actuated arrangement, which may otherwise be constructed according to Fig. 2.

Figs. 10 and 11 show reed suspension devices which may be used with both types of machines. Shaft 38' is shown as I-beam shape in cross-section; the ends of the shaft are of course provided with cylindrical gudgeons. Brackets 107 are fixed to the shaft 38' at a plurality of spaced points, only one being shown on Figs. 10 and 11. To each bracket 107 is adjustably secured a second bracket 108, adjustment being realized through screw bolt 109, and the parts being held in adjusted position by bolts 110. Reed-carrying arms 111 depend from brackets 108, the V-shaped perforated reeds being themselves secured to the said arms by securing screws. Guide rods 112 and 113 may pass through arms 111 as shown.

It will be clear to the skilled in the art that correlation of the parts for knitting may be accomplished, for example during assembly of the machine, in order to achieve any desired results. In connection with particular designs, the monitor head plays its usual significant role.

While the aforesaid embodiments of the invention are the presently-preferred forms thereof, it will be understood that various minor alterations may be made in the details thereof

without departing from the spirit of the invention.

Having thus described the invention, what is claimed is:

1. A knitting machine of the character described comprising a frame, a needle bar mechanism, a guide bar mechanism, a work take-up mechanism, and driving mechanism therefor, said driving mechanism comprising a source of motive power mounted on said frame within its confines and intermediately of the end walls thereof, a pair of drive shaft elements connected to said source of power, an operative connection between said needle bar mechanism and each of said drive shaft elements for reciprocating said needle bar mechanism, an operative connection between said guide bar mechanism and one of said drive shaft elements for oscillating said guide bar mechanism, and an operative connection between said work take-up mechanism and the other of said drive shaft elements.

2. In a knitting machine of the Raschel type, a reciprocable needle bar mechanism providing a plurality of rows of needles, a guide bar mechanism cooperable with one of said rows of needles and comprising a guide bar and a swing shaft from which said bar depends, a second guide bar mechanism essentially paralleling said first-named guide bar mechanism and cooperable with another of said rows of needles and comprising a second guide bar and a swing shaft from which said second guide bar depends, means for actuating said mechanisms, and means for coordinating their relative movement.

3. In a knitting machine of the Raschel type, a guide bar mechanism comprising a swing shaft, brackets secured thereto and depending therefrom, guide pins extending from said brackets, a guide bar slidably mounted on said pins, whereby said bar may describe the oscillatory movements of said swing shaft and may also reciprocate relatively thereto, and means for reciprocating said guide bar, said means comprising a monitor head and a pull member for moving

said guide bar in one direction and coil springs mounted on said pins for moving said guide bar in the other direction.

4. A knitting machine of the character described comprising a frame, a needle bar mechanism, a guide bar mechanism, and driving mechanism therefor, said driving mechanism comprising a source of motive power mounted on said frame within its confines and intermediately of the end walls thereof, a pair of drive shaft elements connected to said source of power, an operative connection between said needle bar mechanism and each of said drive shaft elements for reciprocating said needle bar mechanism, and an operative connection between said guide bar mechanism and one of said drive shaft elements for oscillating said guide bar mechanism.
